Primary Examiner — Susan Bennett Hattan*Assistant Examiner* — Marie Fast Horse(74) *Attorney, Agent, or Firm* — Notaro, Michalos & Zaccaria P.C.(57) **CLAIM**

The ornamental design for a mounting card for tie, as shown and described.

DESCRIPTION

FIG. 1 is a front, top, left perspective view of a mounting card for tie showing my design therefor;

FIG. 2 is a front elevational view thereof;

FIG. 3 is a rear elevational view thereof;

FIG. 4 is a left side elevational view thereof;

FIG. 5 is a top plan elevational view thereof;

FIG. 6 is a bottom plan elevational view thereof;

FIG. 7 is a perspective view of a mounting card for tie showing a second embodiment of my design;

FIG. 8 is a front elevational view thereof;

FIG. 9 is a rear elevational view thereof;

FIG. 10 is a left side elevational view thereof;

FIG. 11 is a top plan elevational view thereof; and,

FIG. 12 is a bottom plan elevational view thereof.

The broken lines in FIGS. 1, 2, 3, 7, 8 and 9, are meant to show stitching and form part of the design.
